UNITED STATES PATENT OFFICE.

WINFIELD S. JONES, OF BREA, CALIFORNIA, ASSIGNOR, BY DIRECT AND MESNE ASSIGNMENTS, OF ONE-EIGHTH TO HAROLD U. BAKER, OF LOS ANGELES, CALIFORNIA; THREE-SIXTEENTHS TO ELMORE D. JONES, OF TAFT, CALIFORNIA; AND ONE-FOURTH TO L. T. McCUTCHEON AND ONE-FOURTH TO J. F. McMAHON, BOTH OF LOS ANGELES, CALIFORNIA.

CUTTER.

Application filed May 15, 1923. Serial No. 639,091.

This invention relates to cutters, and particularly to what may be termed a pipe cutter for use in cutting any form of pipe such as drill stems for use in wells. The invention has for an object the provision of a device of this character which will sever pipe upon downward feeding of the device. A further object is the provision of a device which is readily removable, when it is used for cutting pipe within a well hole without in any manner breaking the cutters.

Assuming oil well practice as an example of the use of the present device, this device has the advantage of readily being removable from the well hole in case of any impairment of the device or due to collapse within the well hole because of shifting formations or freezing of the pipe, or in the case of rotary well apparatus a shortage of mud resultant upon breaking down of the pumps or hose, or any of the numerous devices for maintaining circulation of mud in the well hole. Numerous cutters are now on the market that work on what may be termed an upward motion, with the result that any impairment in the well hole such as freezing or lack of circulation of mud will cause a loss of the cutter, or if an attempt be made to withdraw the cutter from the hole, of tearing all projections loose within the well hole, thereby ruining the cutters and likewise causing other damage. Furthermore, a cutter that is not readily removed from the well hole may cause a loss of the well hole by the necessity of leaving the cutter and the pipe within said hole.

The invention has for further objects the provision of a cutter which is novel in construction, fool-proof in its operation and which will not readily get out of order.

With the above and other objects in view, the invention consists in the provision, formation, construction, association and relative arrangement of parts, members and features, all as shown in one embodiment in the accompanying drawings, described generally and finally pointed out in claims.

In the drawings:

Figure 1 is an elevation, partly in section, of the improved cutter shown in position upon a drill stem;

Figure 2 is an enlarged view of the device

shown in Figure 1, and showing the cutter in cutting operation upon the drill stem;

Figure 3 is a fragmentary cross sectional view on an enlarged scale of a trip element associated with the cutter;

Figure 4 is a transverse section, on an enlarged scale, of certain features of the device, said view being taken on the line 4-4 of Figure 2, and looking in the direction of the appended arrows;

Figure 5 is a fragmentary view, certain parts being in section and on an enlarged scale, of the cutter in operation upon the drill stem;

Figure 6 is a transverse sectional view of features of the device taken on the line 6-6 of Figure 2, and looking in the direction of the appended arrows; and

Figure 7 is a transverse sectional view of other features of the device, taken on the line 7-7 of Figure 1 and looking in the direction of the appended arrows.

Corresponding parts in all the figures are designated by the same reference characters.

Referring with particularity to the drawings, the improved cutter is designated as an entirety and in one embodiment by A, and a drill stem pipe upon which the cutter is adapted to operate is designated by B. It is to be understood, however, that the device A is adaptable for cutting pipe other than drill stem pipe. The cutter A includes several elements adapted to be associated together and to cooperate in the performance of the cutting operation upon pipe such as the drill stem pipe B, and at a desired zone upon said drill stem pipe B. Said elements comprising the device A, without reference to their relation, consist in a cutter shell a, a cutter blade or series of cutter blades b associated with the shell a, a driving sleeve c for operating at desired points or times the cutter or cutters b, a stool cage d for confining stool or stool members e, a frictional tubing engaging sleeve f carrying the spring friction members g, and a latch barrel h carrying a latch member j.

It will be noted that the cutter shell a varies in cross section, depending upon its location, the cross section being largest at its top, as shown at 1 and formed with a tapered screw-threaded annular socket, as

shown at 2, whereby drive pipe, as 3, may be screw-threaded within said tapered socket 2, and the lowermost end as 4, of the shell *a*, is screw-threaded for engagement with a 5 screw-threaded portion 5 of the latch barrel *h*, the latch barrel in turn being formed at its lowermost end with a tapered screw-threaded socket 6. The latch barrel *h* is further provided with screw threads as 10 shown at 7 for receiving a screw-threaded portion 8 of the friction carrier sleeve *f* thereby to temporarily connect the same with said latch barrel *h*. In this connection it is to be observed that the latch barrel *h* is screw-threaded externally and internally at the portions 4 and 7 respectively, and that the sleeve *f* is formed with a shouldered portion, as 9, for engagement with the end of the friction carrier *f*; 15 furthermore, the friction carrier sleeve is enlarged at the part 10 and then reduced as to internal diameter, as shown at 11, with an upper zone thereof, as shown at 12, enlarged, then reduced as shown at 13 so as 20 to form a shoulder 14 between the parts 12 and 13. It is to be observed that the formation and association of the cutter shell *a*, the friction carrier sleeve *f* and the latch barrel *h* is such as to present a flush outer 25 surface, with the periphery of the sleeve *f* in close working engagement with the inner surface of the cutter shell *a*. The sleeve *f* has associated therewith and at the part 15, 30 a bent spring or springs or friction member or members *g* which are attached by means 35 of rivets 16 to the carrier sleeve *f*, and receivable within a slotted portion 17 in the enlargement 12 of said sleeve *f*. It is intended that this spring or series of springs 40 *g* should bear against the periphery of the pipe to be cut, such as the drill stem *B*. The reduced portion 13 of the sleeve *f* is adapted to be received in a space formed by the cutter shell *a* and the stool cage *d*, as shown at 45 18. The stool cage *d* is formed with an enlargement 19, the periphery of which is in close engagement with the inner surface of the cutter shell *a*, as shown at 20, and then formed with a portion 21 spaced from the 50 inner surface of the member *a* so as to accommodate the part 13 of the sleeve *f*, as has been stated; in other words, within the space 18. This formation and construction permits guiding of the member *f* in certain 55 of its movements when the tool is in operation, which operation will be described in detail later. Immediately above the member *d* is the member *c* which is formed with a flange member 22, the periphery of which 60 is in close working engagement with the inner surface of the shell *a* and the remaining part of which, as 23, is spaced from the inner surface of the member *a*, the flange 22 and the part 23 forming a shoulder 24 for 65 the purpose of confining one end of an ex-

pansible member 25. Carried by the member *a* and on the interior thereof and adapted to bear against the periphery of the part 23 of the member *c* are stops 26 which act as an abutment for confining the end 27 of 70 the expansible member 25. The shell *a* is slotted at a plurality of points, as 28, and the cutter elements *b* are receivable within said slots and held to the member *a* by means of pins 29. The cutters *b* are curved at the 75 point 30 and a zone near the extremity of the member *c* is tapered, as shown at 31 so as to readily engage the part 30, and upon upward movement of the member *c* forces the cutters inwardly (swinging on the pins 80 29) as shown in Figure 2 to perform a cutting operation upon the work *B*. Likewise carried by the member *a* is a key *k* receivable within a groove 32 in the member *c*, it being noted that the head portion, as 33 of 85 said member is enlarged for the purpose of receiving said key and likewise for the purpose of affording sufficient area for operating the cutter *b*.

In the operation of the cutters it is de- 90 sirous that the cutters should not be subjected to undue lateral strain and the keys act to prevent a shearing of said cutters when the device is being operated, as will more clearly appear later. The members 95 *c* and *d* at the enlarged portions 22 and 19 respectively, are each one formed with a ball-bearing race shown as 34 and 35 within which races are adapted to be confined bearing members 36, and an annulus *m* formed 100 with flanges 37 and 38 is adapted to join the members *c* and *d* by the flanged portions 37 and 38 entering grooves 39 and 40 respectively in the enlargements 22 and 19. The annulus *m* is not in tight engagement with 105 the members *c* and *d*, but is sufficient to permit a relative rotation, when necessary, as between the said members. The stools or stop elements *e* are normally held in position of service by a spring 41 confined within an 110 annular groove 42 in the part 19 of the member *d*, said springs being likewise receivable in cut-away portions 43 of the stools *e*. Said stools *e* are formed with enlarged heads 44 having joined therewith leg portions 45, and 115 said heads are formed with tapered or inclined ends 46 whereby when the device as an entirety is inoperative, the spring member 41 by forcing the stools *e* outwardly so as to be against the inner surface of the 120 member *a*, will cause the inclined ends to engage the end portion of the member *d* shown at 47. In this connection it is to be noted that the stool cage *d* is formed with a series 125 of slots 48 within which the stools *e* are confined and the end portion 47 is in reality one of the walls bounding one portion of one of the slots 48.

The latches *j* are receivable within slotted 130 portions 49 of the latch barrel *h*, and said

latches *j* are held in position by means of pins 50 passed therethrough and into the wall of the member *h*, said latches *j* being formed with a shouldered portion 51, with a coil spring 52 wrapped about the pin 50 and having one end, as 53, engaging the shoulder 51 and the other end 54 engaging with a wall bounding the slot 49. Said latches are formed with notched portions 55, and limiting pins 56 are carried by the member *h*, said pins 56 being received in such notches 55 when the latch or latches *j* are moved in one direction under actuation of the spring member 52 to normally lock the member *f* and member *h* together. The latch is formed with a shouldered end as shown at 57 and the normal position for said latch or latches is that shown in Figure 3, the latches being held in such position; that is to say, inwardly from the slot 49 by means of a small wire or other medium 58 passed through an opening in the said latch or latches. The latch when in the position shown in Figure 3 is adapted to be received in a keeper notch or slotted portion 59 of the member *f* and thus prevent the member *f* from becoming disconnected from the member *h*.

The operation, uses and advantages of the device just described are as follows: Assume the parts in the position shown in Figure 1 in which it will be noted that the cutter elements *b* are out of contact with the periphery of the drill stem *B*. The latch *j* is in position of service; that is to say, maintaining the members *f* and *h* in working relation and in such a relation that the same do not unscrew. The member *A* has been lowered by means of the drive tubing 3 and the lower end of said member *A* may carry a wash-over shoe, screw-threaded to the threaded portion 6, said wash-over shoe not being shown. The stool *e* is out of position of service and the spring member *g* is in engagement with the periphery of the drill stem *B*. When the latch *j* contacts with the ledge of a coupling 61 joining two lengths of the drill stem *B*, as 62 and 63, the pin 58 will be sheared and the latch member retracted within the slot 49 of the member *h* and substantially in the position shown in Figure 2 at 64. It may be necessary to revolve the member *A* through the medium of the tubing 3 in order that it may reach a desired location within a well hole and a further turning of the member 3 will, when the latch *j* has been moved out of operative position, to unscrew the member *f* from the member *h*, leave the parts in the position substantially as shown in Figure 2 at 65. Movement downwardly of the member *f* will be constrained by the spring *g* being in frictional engagement with the periphery of the drill stem *B*, and the cutter shell *a* upon its continuance downwardly

will cause the expandable member 25 to be compressed as shown in Figure 2 by the members 26 bearing upon the end 27 of said member 25, which in turn will permit continued movement of the parts to a position 70 where the stool or stools *e* will have their legs in engagement with the ledge 66 of the coupling 61; this being effected by the member *f* moving relative to the shell *a* and forcing the stool *e* so that the leg members 75 thereof engage with the ledge of the coupling 61. Furthermore, this downward movement of the shell *a* relative to the member *f* likewise effects a relative movement as between the members *c* and *a*, inasmuch as 80 the members *c* and *d* are coupled by annular means *m*, the member *f* being received in the space 18 between the members *d* and *a*. The upper end of the member *c* being tapered as shown at 31 will force the cutters *b* into 85 engagement with the periphery of the stem *B* and cut the same substantially as shown in the drawings at 67. These cutters may assume various forms and shapes, that in the drawings showing a cutter provided with a 90 cutting head 68 adapted to form a beveled cut, as shown at 69 in the stem *B*. The member *c* rotates as the member *a* rotates, due to the fact that the members *c* and *a* are keyed as shown in Figure 7. The member 95 *d* does not of necessity rotate, as there are bearing members 36 between said members. If the device *A* is in use in a rotary rig and mud is circulating, it may be desired to relieve any pressure that may exist between the member *a* and the drill stem *B* and the outer surface of the member *a*. This is accomplished by providing perforated openings or vent openings 70 passed through the member *f*. These vent openings 105 likewise accommodate for forcing water or air from within the device *A*. When it is desired to remove the cutter *A* it is only necessary to pull upwardly upon the same, whereupon the spring *g* will still grip the periphery of the stem *B* and cause relative movement of the parts so that the cutters *b* may swing 110 back into their slots 28 in the shell *a* and the member 25 will then expand; the stools will be forced within the slots in the stool cage *d* and the device as an entirety lifted from the well hole without in any manner 115 breaking the cutters *b* or damaging other parts of the device *A*. The pins 29 of the cutters *b* are conveniently held to the shell *a* by being within segmental bores 71 in said shell, as shown in Figure 6 and wherein it will be noted that the edge as 72 of each cutter is in advance of the following edge so 120 as to readily cut the drill stem *B*.

This down-acting cutter readily prevents impairment of the cutters *b* and is a distinguishing feature over devices of a similar nature known to the inventor, in that cutters need not be broken if the cutting ac- 125

tion is not completed, a fact which cannot be accomplished by cutters now on the market that work only on up motion of the drive member, for the reason that the cutters must complete their cutting operation before the cutter as an entirety can be removed from hole. Furthermore, this style of cutter tends to raise the cutter tools from the work upon rotation of the driving pipe 3, instead of 10 causing the cutter blades to dig in and possibly break. Repairs may be easily made by simply withdrawing the device A and replacing the broken part, whereupon the cutting operation may be continued.

15 The parts in the showing are tubular, although it is obvious that shapes other than round may be employed in various parts of the device A. It is a known fact that any blade that works on an up motion in the cutting of pipe must move upwardly to effect the cutting operation, and therefore attempts to lift the pipe being cut in an upward direction oftentimes locking the cutter and breaking the blades, whereas in the device 25 just described, the cutter releases the blades when the pipe moves upwardly and thus eliminates the danger of locking.

One of the distinctive features of the invention is the provision of the friction carrier sleeve *f* provided with the springs *g* which acts as an abutment member, when clutching the tubing, to throw out the stools *e* carried by the cage *d*. As previously indicated, the carrier sleeve or abutment is temporarily connected to the latch barrel *h* carried by the casing *a*, but when released throws the normally inoperative tubing engaging members *e* into position to engage with the shoulder provided by a coupling of the tubing. After the normally inoperative stools *e* are thrown into operative position by the relatively "floating" abutment or sleeve *f*, the entire cutter actuating unit comprising the upper section or driving unit *c* and the lower section or stool cage *d* are moved against the tension of the spring 25 to yieldingly throw the cutters *b*, pivotally suspended from the shell *a*, into engagement with the tubing.

50 It is obvious that various changes and variations may be made in practicing the invention, in departure from the particular description as given, but that said changes and variations may be made within a fair interpretation of the invention as set forth by the scope of the appended claims.

Having thus disclosed my invention, I claim and desire to secure by Letters Patent:

1. A cutter for oil well tubing and the like, including a cutter shell carrying internal suspended cutters, an abutment member having a temporary connection with the shell, a separate cutter actuating member carrying stop elements for engaging with the well tubing, said actuating member being

operatively related to the abutment member and the suspended cutters, and adapted to move the cutters into operating position upon the release of the temporary connection for the said abutment member and the 70 arrest of the latter.

2. A cutter for oil well tubing and the like, comprising a cutter shell carrying internal pivotally suspended cutters, a cutter actuating unit slidably keyed within the cutter shell, tubing engaging means carried by said actuating unit, means within the cutter shell for throwing said tubing engaging means into engagement with the tubing, said means including a sleeve the upper end of which is adapted to engage with the tubing engaging means and the lower end of which is provided with a keeper notch, a latch carried by the cutter shell and adapted to normally maintain the sleeve locked to the cutter shell until engaged by a part of the tubing whereby the sleeve is freed from the shell, and springs carried by the sleeve for engaging with the tubing thereby to hold the same relatively stationary with reference to the tubing.

3. A cutter for oil well tubing and the like, comprising a cutter shell, a sleeve releasably locked to the shell and having springs for frictionally engaging the tubing, internal pivoted suspended cutters carried by the shell, and a cutter actuating device resiliently and slidably mounted in the shell between the cutters and the sleeve and keyed to the shell to rotate therewith, tubing engaging elements carried by said device adapted to be operated by the said sleeve to engage the tubing whereby the cutter actuating device will be held relatively stationary on the tubing while the cutter shell descends to cause the cutters to move inwardly and cut the tubing.

4. A cutter for oil well tubing and the like, comprising a cutter shell, a tubing engaging sleeve having a releasable connection with the cutter shell, cutters pivotally suspended in the shell, a cutter actuating unit mounted between the cutters and the sleeve and slidably keyed to the cutter shell, and normally inoperative tubing engaging means carried by the cutter actuating unit and operated by said sleeve.

5. A cutter for oil well tubing and the like, comprising a cutter shell, a tubing engaging sleeve having a releasable connection with the cutter shell, cutters pivotally suspended in the shell, a cutter actuating unit including an upper cutter-engaging section slidably keyed to and resiliently mounted within the shell and a lower section having a rotary joint-connection with the upper section, and tubing engaging means carried by the lower section and actuated by the sleeve.

6. A cutter for oil well tubing and the

like, comprising a tubular cutter shell, a latch barrel at the lower end of the cutter shell, cutters pivotally mounted in the shell, a friction carrier sleeve within the cutter shell, means for detachably locking the carrier sleeve to the latch barrel, a cutter engaging driving sleeve yieldingly mounted in the cutter shell and keyed to rotate therewith, a stool cage connected with the driving sleeve whereby it may remain stationary with reference to said sleeve, tube-coupling-engaging stool members carried by said stool cage, and the lower end of said stool cage and the upper end of the friction carrier being adapted for relative telescopic movement whereby the friction carrier when unlocked from the cage will actuate the stool members.

7. A cutter for oil well tubing, and the like, comprising a tubular cutter shell, cutters pivotally carried by the shell member, a member having means for frictionally engaging the pipe to be cut, means for normally locking said member with the cutter shell and releasing it to permit it to clutch the pipe while the cutter shell may move longitudinally with reference thereto, a cutter controlling member slidably keyed to the cutter shell, resilient means for cushioning said cutter actuating member in its sliding movement with reference to the shell, and means associated with said cutter actuating member and adapted to be operated by the friction member to cause said cutter actuating member to move the cutters into cutting relation to the pipe.

8. A cutter for oil well tubing and the like having enlarged coupling portions, comprising a tubular cutter shell adapted to

telescopically fit over the tubing, cutters pivotally carried by the cutter shell, a member comprising two relatively rotatably connected sections, one of which sections is slidably keyed to the cutter shell and is adapted to move the cutters inwardly toward the tubing to be cut, a spring for maintaining said member in normally inoperative relation with reference to said cutters, tubing coupling engaging means carried by the lower section of said member, and tubing engaging means releasably locked to the shell.

9. A cutter for oil well tubing and the like having enlarged coupling portions, comprising a tubular cutter shell adapted to telescopically fit over the tubing, cutters pivotally carried by the cutter shell, a member comprising two relatively rotatably connected sections, one of which sections is slidably keyed to the cutter shell and is adapted to move the cutters inwardly toward the tubing to be cut, a spring for maintaining said member in normally inoperative relation with reference to said cutters, tubing coupling engaging means carried by the lower section of said member, and tubing engaging means releasably locked to the shell but comprising a friction carrier sleeve having tubing engaging springs carried therewith and also having a keeper notch, and a latch member carried by a part of the cutter shell and normally engaging said keeper notch but adapted to be released therefrom when engaged by a coupling of the tubing.

In testimony whereof, I have signed my name.

WINFIELD S. JONES.
